UNITED STATES PATENT OFFICE.

THOMAS A. RICHARDSON, OF VERONA BOROUGH, AND EMANUEL WOODINGS, OF OAKMONT BOROUGH, PENNSYLVANIA, ASSIGNEES TO VERONA TOOL WORKS, OF PITTSBURGH, PENNSYLVANIA, A CORPORATION OF PENNSYLVANIA.

LIFTING-JACK.

1,269,644.

Specification of Letters Patent. Patented June 18, 1918.

Application filed January 26, 1914. Serial No. 814,393.

To all whom it may concern:

Be it known that we, THOMAS A. RICHARDSON and EMANUEL WOODINGS, are citizens of the United States, and residents of Verona borough and Oakmont borough, in the county of Allegheny and State of Pennsylvania, have invented a new and useful Improvement in Lifting-Jacks; and we do hereby declare the following to be a full, clear, and exact description thereof.

Our invention relates to jacks, its object being to provide a compact jack occupying but little height, so providing a jack of less weight and bulk, this being the character of jack needed for different classes of work, such as track ballasting, and the like.

It comprises, generally stated, the combination of a jack frame, a toothed rack, a hand lever carried in a pivot pin supported on the frame, a pawl pivoted on the hand lever between the rack and pivot pin, and a detent mounted on the pivot pin and extending up to engage with the rack beyond the pawl. It also comprises other improvements as hereafter set forth.

In the accompanying drawings, Figure 1 is a view of the jack in the operation of lifting; Fig. 2 is a like view showing the method of tripping the jack; Fig. 3 is a transverse section on the line 3-3, Fig. 1; Fig. 4 is a view of the end of the hand lever with the pawl or detent; Fig. 5 is a modification.

The frame 2 of the jack is formed of iron or steel cast to shape, and has therein the guideway 3 in which is mounted the toothed rack 4, said toothed rack being shown with the foot 5 and having preferably the grooves 6 in which the ribs 7 on the frame enter to guide the movement of the rack bar. The jack frame has the pawl pocket 8 at one side of the guideway 3, which supports in bearings 15 the main pivot pin 9 on which is mounted the hand lever 10. This hand lever has at its inner end between the pivot pin and rack the pawl seat 11 which has the form of a recess slightly more than a half circle, so as to retain therein the bearing 13 of the pawl 12.

As shown in Fig. 3 the portion 14 of the pawl pocket near the guideway 3 is formed of the same width as the guideway and the forward end of the hand lever 10 and the body of the pawl 12 enter into this por-

tion 14 of the guideway. The pocket is widened where it is provided with the bearings 15 of the pivot pin 9, such widened portion 17 being of an increased width corresponding to the thickness of the side arms 19 of the detent 18, the head 20 of the detent being of a greater width than the top of the pawl 12, while the arms 19 thereof extend down within the widened portion 17 of the pawl pocket and fit around and having their support or bearing on the pivot pin 9 as shown. Thus a very compact form of jack is provided in which the hand lever may be mounted low down in the jack frame, and the detent 18 may be brought by its mounting close to the top of the pawl, while a short pawl may be employed effectively to do the work and it is practicable to form a jack having great strength and having a body of a foot or less in height. As will be noted in Fig. 3 the arms 19 of the detent 18 will serve to center the hand lever within the frame filling the enlarged pawl pocket at this point. These arms 19 also overlap the pivot portion 13 of the pawl body 12 where it is seated in the hand lever retaining it in place, so that even though it may swing out of the narrow portion 14 of the pawl pocket, by means of these side arms or wings, it is always held laterally in position on the hand lever and hand lever with its pawls and detent are all properly centered within the pawl pocket.

In the operation of the jack, the pawl and detent are normally held by their weight, in engagement with the rack and the rack is lifted by the swing of the hand lever tooth by tooth, being held in position by the detent when the pawl drops down to engage another tooth.

When it is desired to trip the jack, it is only necessary to give a longer downward stroke to the hand lever, when it carries the pawl back against the detent, as indicated in Fig. 2, and so pushes the detent from contact with the rack. Upon raising the hand lever the pawl and detent again swing forward to engage the rack. In Fig. 5 is shown a modification of the invention in which the detent 25 instead of having arms fitted outside of the hand lever, has a centrally extending arm 26 which fits around the pivot pin 27 and within a central seat 28 formed for its reception in the

hand lever 29, thus providing for the mounting of the detent directly on the pivot pin, and giving some of the same advantages as the preferred construction shows in the other figures of the drawing.

By our invention we are enabled to provide a very compact and strong jack and to mount the detent at a lower position in which it has sufficient strength to fully support the load on the jack, and in which it can also be quickly and easily tripped when necessary to drop the jack; while the jack can be made so low that in many cases the load can be carried direct upon the rack, instead of requiring the preliminary lifting by means of the foot thereof.

What we claim is:

A jack in combination with a frame, a

toothed rack therein, a hand lever mounted on a pivot pin supported in the frame having a recessed seat at its forward end, a pawl mounted in said recessed seat between the rack and the pivot pin, and a detent having depending side arms fitting on both sides of the hand lever and mounted on the pivot pin and overlapping the journal of the pawl where it is mounted in the hand lever.

In testimony whereof, we the said THOMAS A. RICHARDSON and EMANUEL WOODINGS have hereunto set our hands.

THOMAS A. RICHARDSON.
EMANUEL WOODINGS.
